UNITED STATES PATENT OFFICE.

JOSEPH A. AMES, OF NASHVILLE, TENNESSEE.

WATERPROOF FOOTWEAR.

1,290,692.

Specification of Letters Patent.

Patented Jan. 7, 1919.

Application filed March 5, 1918. Serial No. 220,439.

To all whom it may concern:

Be it known that JOSEPH A. AMES, a citizen of the United States, residing at Nashville, in the county of Davidson and State 5 of Tennessee, has invented certain new and useful Improvements in Waterproof Footwear, of which the following is a specification.

This invention relates to water-proof foot 10 wear and is particularly directed to an improved method of making such foot wear as well as the article itself.

One of the prime objects of my invention is one wherein the foot wear constructed as 15 I have outlined may be readily repaired such as by half soling or by completely soling the goods without in any way interfering with its water-proof properties. In this connection, it may also be understood that my invention contemplates the combination of an 20 ordinary rubber upper with a leather outer sole or the well known composition equivalents of either one or both.

The preferred embodiment of my invention will be better understood by referring 25 to the accompanying sheet of drawings in which similar characters of reference designate corresponding parts and in which,

Figures 1 to 6 inclusive represent the various stages of manufacture of my improved 30 article.

In Fig. 1, the ordinary type of insole 1 is shown which insole is provided with a depending rib of any desired form such as 35 is shown at 2. This structure as shown in Fig. 1 is then preferably coated with sheet or liquid rubber as is indicated at 3 in Fig. 2 whereupon the upper 4 as shown in Fig. 3 is applied. Preferably, this upper is worked 40 in along the edges, heel and toe of the insole to pass over the rib 2 as shown at 5 and to overlap at approximately the center of the insole as shown at 6. After the foot wear has been thus built up, the entire structure is 45 again coated with sheet or liquid rubber as is shown at 7 in Fig. 4. This structure is then placed in a vulcanizing oven and the rubber vulcanized to the desired degree. An entire water proof shell is thus formed and 50 this structure is then ready to receive the welt 8 as shown in Fig. 5. This welt is preferably attached in the well known manner as by stitches 9. It will be noted that these 55 stitches do not perforate the shell proper but only pass through its ribbed projection. After this, the space between the ribs may

be filled with fiber, ground cork or any other desirable substance as indicated at 10 and the outer sole 11 then applied by stitching through the welt as is shown at 12. 60

It will thus be observed that an entirely water proof shell is provided onto which an outer sole of any desired material may be applied. This outer sole may also be replaced without injuring the shell and further 65 the upper is protected by the outward projection of the welt and outer sole against the action of stones or other objects which might scratch and tear the goods when stepped upon. Also, the outer sole may be of 70 material which is sufficiently stiff to prevent the wearer from feeling stones and pebbles as they are stepped upon and in addition, this outer sole may also be made of material which will considerably outlive the present 75 day well known rubber or rubber composition materials.

What I claim is:

1. The method of producing water proof foot wear which consists in forming an upper around an insole to form a shell, applying rubber to at least one surface of said shell to form a continuous coating, vulcanizing, and then attaching an outer sole. 80

2. The method of producing water proof foot wear which consists in forming an upper around an insole to form a shell, applying rubber to at least one surface of said shell to form a continuous coating, vulcanizing, securing a welt to the structure thus 90 formed, and then attaching an outer sole by means of said welt.

3. The method of producing water proof foot wear which consists in forming an upper around an insole, coating the exterior 95 surface of the assembled structure of upper and insole with rubber, vulcanizing, and then attaching an outer sole.

4. The method of producing water proof foot wear which consists in coating the bottom of an insole with rubber, forming an upper around the coated insole, coating the exterior surface of the assembled structure of upper and insole with rubber, vulcanizing, securing a welt to the structure thus 105 formed, and then attaching an outer sole by means of said welt.

5. The method of producing water proof foot wear which consists in forming an upper around an insole so that the entire bottom of the insole is covered, coating the exterior surface of the assembled structure of 110

upper and insole with rubber, vulcanizing, securing a welt to the structure thus formed, and then attaching an outer sole by means of said welt.

- 5 6. The method of producing water proof foot wear which consists in forming a rib around the bottom of an insole and covering the bottom of such insole and rib with rubber, forming an upper around said insole to lie in engagement with said rib, coating the structure thus far assembled with rubber, vulcanizing, securing a welt to said rib and then securing an outer sole to said welt.
- 10 15 7. Water proof foot wear comprising an inner sole, a rib secured to the bottom of said inner sole and an upper formed around said inner sole and rib all forming a superstructure, a coating of vulcanized rubber

over said superstructure, a welt also carried 20 by said superstructure and secured to said rib, and an outer sole attached to said welt.

8. Water proof foot wear comprising an inner sole, a rib secured to the bottom of 25 said inner sole, a coating of vulcanized rubber over said rib and inner sole, an upper formed around said inner sole in engagement with said rib all forming a superstructure, a coating of vulcanized rubber over said superstructure, a welt secured to said 30 rib, and an outer sole secured to said welt.

In testimony whereof I affix my signature in presence of two witnesses.

JOSEPH A. AMES.
